ATTORNEY.

UNITED STATES PATENT OFFICE.

CYRUS W. NEBLETT, OF LAVERNIA, TEXAS.

SUPPORTING STRUCTURE.

1,286,391.

Specification of Letters Patent.

Patented Dec. 3, 1918.

Application filed December 28, 1917. Serial No. 209,332.

To all whom it may concern:

Be it known that I, CYRUS W. NEBLETT, a citizen of the United States, residing at Lavernia, in the county of Wilson and State 5 of Texas, have invented certain new and useful Improvements in Supporting Structures, of which the following is a specification.

My invention relates to a supporting structure and particularly to one for use in out- 10 door work, as on the farm, particularly to support a scale for weighing material like cotton. A device of this character must be portable, and to this end, I have provided an article which is readily foldable for trans- 15 portation, and the foldable construction permitting ready adjustment and leveling of the structure. As well, I have aimed to provide a novel construction, which can be cheaply manufactured and which will prove 20 substantial and durable in use.

One preferred embodiment is illustrated in the accompanying drawings, wherein:—

Figure 1 is a view in front elevation of 25 my improved device showing a scale beam supported thereby;

Fig. 2 is an elevation taken at right angles to Fig. 1, and

Fig. 3 is a top or plan view.

Referring specifically to the drawings, 30 four bars 4 collectively form a square or rectangular frame. Each bar at each end is deflected outwardly at an angle into a lug 5. Between the lugs 5, substantially flat portions 6 of supports or legs 7 are disposed. 35 Rivets or other suitable fastening means 8 pass through the lugs 5 and portions 6, to pivotally connect the legs to the frame and the bars 4 together. This construction is

one which may be readily leveled on uneven ground due to the pivotal connection of the 40 supports 7, and it is one in which the frame may be folded flat against the legs or the legs flat against the frame in order that the article may be easily transported and will occupy a small space in shipment. 45

A bridge bar 9 is secured by means of rivets or other fasteners 10 to two of the bars 4 and substantially centrally thereof. To the bar 9, a ring 11 is preferably fastened to facilitate fastening or suspension of a pend- 50 ent chain or flexible element 12 therefrom. The element 12 may terminate in a ring 13 to which a scale beam or other preferred form of scale or any desired article 14 may be 55 removably hooked or suspended.

I have shown merely one preferred embodiment of the invention, in view of which fact, changes in the details of construction may be resorted to, without departing from 60 the spirit and scope of the invention, as defined by appended claim.

I claim:—

A supporting structure, comprising bars arranged to inclose a space and having 65 their ends outwardly deflected to form lugs which are spaced apart, legs between the lugs, fastenings passing through the lugs and legs and connecting the bars and legs, and a bridge piece attached at its ends to 70 opposite frame bars.

In testimony whereof I affix my signature in presence of two witnesses.

CYRUS W. NEBLETT.
